SCREW CLAMP

George B. Bosco, Chicago, Ill.

Application January 17, 1938, Serial No. 185,286

6 Claims. (Cl. 25—131)

The present invention relates to forms for molding concrete and masonry work, and more particularly to means for removably supporting the forms in operative position and the process of arranging and employing the forms in assembling a masonry structure.

It is an object of this invention to provide a new clamp member for assembling concrete forms and the like which is simple in construction and capable of being readily assembled and disassembled and readily extracted from the forms, as well as from the masonry without damaging the work.

It is a further object of this invention to provide a clamp for masonry forms having a tie-rod portion capable of being located interiorly of the form and thus centrally of the final cast masonry but which can be extracted relatively freely therefrom whether the masonry is in the "green" or finally hardened condition.

A yet further object of the present invention is to provide a device as above wherein the final removal of the clamping assembly from the work leaves the terminal portions of the resulting aperture clear and unobstructed so that it can be readily pointed to close the aperture and preserve uninterrupted the exterior surface character of the masonry.

An additional object of the present invention is to provide form clamping means of the general character defined above having a plurality of separable portions adapted to be individually removed from the work after hardening thereof, the various portions being readily separable or having special means thereon adapted to be engaged for facilitating removal from the work.

The present invention comprehends the provision of composite clamping means for concrete forms and the like which may be embedded in the work and which comprises a central member adapted to space portions of the form, as well as to tie them together, having, in combination, an element which protects the aforementioned central member and permits relatively free removal thereof from the work at all times. According to the present invention the protecting member may be so constructed as to be relatively readily removed from contact with the masonry after the other element of the combination has been withdrawn therefrom.

It is, accordingly, an additional object of the present invention to provide a clamping member having a central tie-rod in combination with a protecting enclosing member formed of resilient, flexible, extensible or elastic material which,

when caused to expand longitudinally, tends to shrink in transverse dimension in order to permit ready extraction from an enclosing body of hardened masonry.

5 A still further object of the present invention is to provide a simplified and improved method and means for spacing opposed portions of concrete forms, using threaded clamping bars in combination with a readily available and elemental type of fastening for engaging the threads and a portion of the form for retaining the bars axially with respect to the form.

Yet another object of the present invention is to provide a method and means for assembling 15 sectional, poured masonry structures by the use of forms which are secured progressively to each newly cast section of masonry, and contemplates the provision of a firm, rigid form structure at all times capable of withstanding pressure of the interior masonry mass without the necessity of additional bracing or staging and which is readily removable from the "set" work, leaving the surface thereof free from imperfections or projections.

20 Numerous other objects and advantages will 25 more fully appear during the course and progress of the following specification.

Figure 1 is a perspective view of a concrete 30 form constructed in accordance with the present invention.

Figure 2 is a detail plan section taken on the line 2—2 in Figure 1.

Figure 3 is a sectional plan view showing an 35 alternative concrete form constructed in accordance with the present invention.

Figure 4 is a detail plan section taken on the line 4—4 in Figure 3.

Figure 5 is a sectional elevation through the 40 finished wall showing the screw clamp parts in disassembled relationship to indicate the removal thereof from the work.

Figure 6 is an elevational view of the conical 45 sleeve member taken on the line 6—6 in Figure 5.

Figure 7 is a perspective view of a tool for 50 withdrawing the conical members from the finished work.

Figure 8 is a vertical sectional elevation of yet another preferred embodiment of the present invention.

55 Figure 9 is a vertical elevational view of a modification of the structure shown in Figure 8.

Figure 10 is a detail sectional plan view taken on the line 10—10 in Figure 8.

Figure 11 is a sectional elevation taken through the finished masonry wall constructed with the

assistance of the form members shown in Figures 8 and 10.

Figure 12 is a sectional elevational view through a preferred type of form assembly constructed in accordance with the present invention.

Figure 13 is a sectional detail elevation through a portion of the masonry structure cast in the form shown in Figure 12.

Figure 14 is a perspective detail view of a break-back employed on the clamping bars shown in Figure 12.

Referring to the figures of the drawing wherein the invention is disclosed more in detail, and particularly Figures 1 and 2, there is disclosed a form for a masonry column comprising form faces 10, 12, 14 and 16 arranged to form a rectangular enclosure. These form faces may be made in the conventional manner from a plurality of blanks joined by the battens 18 and 20. The liners or whalers 22 of relatively heavy framing material are clamped on either side of the form through the agency of the screw clamps 24 to resist the disruptive forces of considerable magnitude produced interiorly of the mold during the casting of the plastic masonry material.

Each screw clamp comprises an integral bar member 26 extending through aligned apertures in the opposed whalers. Both ends of the bars are threaded as at 28 to accommodate the clamping wing nut 30. As clearly shown in Figures 1 and 2, the bar 26 may be so arranged that it is spaced from the battens 32 which are fastened to the side form faces. A pair of wedges 34 are then driven between the battens and the bar to rigidly position these side form faces. In order to assist in assembly, the whalers may be toenailed to the form faces by nails 36.

The disassembly of the above described structure, after the masonry has hardened or set, will be a relatively simple matter. After the nuts 30 have been loosened and removed from the work, the wedges 34 and the bars 26 may be readily driven out after which the form faces can be readily separated and pulled apart.

The alternative preferred structure shown in Figures 3 to 5 is adapted for use in forms for casting relatively expansive masonry walls or partitions wherein opposed sections of form faces of considerable extent must be tied together by clamps extending through the space in which the masonry casting is to be made. In accordance with this embodiment the opposed form faces 10 and 14 constitute the opposite walls of the form that are stiffened through the agency of studding members 38. The opposed, parallel whalers 22 engage the opposite outer faces of the studs 38 and clamp the whole assembly therebetween through the agency of the screw clamps 24 extending through suitable aligned apertures in the whalers, as well as the form faces.

Attention is directed to the fact that the studding members 38 are preferably arranged symmetrically with respect to the clamping bar so that the clamping forces will be evenly distributed to the form faces. For the purpose of permitting complete and easy removal of the clamping bar 26 from the work after setting and hardening has taken place, there is provided in accordance with the present invention a tubular member 40 which is slidably arranged on the bar 26. It will be obvious in accordance with this disclosure that, since the tube 40 surrounds and encloses the bar 26 thereby protecting it from contact with the masonry, the latter member may be readily withdrawn from the work at any time by merely loos-

ening the nuts 30 and applying axial pulling force. According to one aspect of the present invention the tube 40 may be permitted to remain permanently within the work in which case it 5 may comprise any suitable inexpensive tubing, such for example as paper or cardboard tubing. On the other hand, if reinforcing strength is desired, metallic tubing may be inserted at this point.

It is generally desirable in the present art to provide a finished wall free from apertures, as a result of which the opening left by removal of the bar 26 must be cleared so that it can be filled or pointed with a suitable mortar mixture. To 15 this end there is provided in accordance with the present preferred embodiment a pair of resilient, contractable sleeves 42 formed of rubber or the like and slidably arranged on the bar 26 adjacent the ends of the tubular sleeve 40. It will be noted that the sleeves 42 are of generally conical form, the ends being truncated at a transverse dimension corresponding with the diameter of the tubular sleeve 40. The base portions of the sleeves 42 are, as clearly shown in Figures 3 and 4, arranged in abutment with the inner faces of the 20 form faces 10 and 14 with their other extremities abutting the ends of the central tubular member. It will be obvious from this disclosure that the sleeve members 40 and 42 may be used to accurately space the form faces 10 and 14 in accordance with the wall thickness desired.

As shown more clearly in Figures 4 and 6, each of the conical sleeves 42 is provided with an annular recess 44 extending from the central 25 bore, the recess being bounded adjacent the base portion of the cone by means of the inwardly extending lip 46. The lip 46 is in turn interrupted by radial relieved portions 48 which are configurated to permit the passage of the end of the tool shown in Figure 7. The tool has a shank portion 50 mounted at its end with a fixed, transversely extending bar 52. After the end of the tool is inserted into the face of the cone sleeve and rotated through a small arc, the ends of the bar 52 engage under the lip 46 so that the tool may be actuated by pulling upon the handle 54 to draw the cone member reversely from the finished wall.

Figure 5 clearly illustrates the removal of the 30 clamping screw assembly by first disassembling one of the nuts 30 and then withdrawing the bar 26 and the sleeves 42, using the procedure hereinbefore defined. The conical apertures formed by removal of the conical sleeves 42 are 35 shown provided with a mortar filling 56 bonded directly to the masonry work piece so that the exterior appearance of the finished wall is uniform.

The alternative preferred form for masonry construction shown in Figures 8 to 10 inclusive comprehends the employment of a tubular member 40 slidably mounted on and enclosing the bar 26 which tubular member, however, extends preferably through the form faces 10 and 14 so as to project substantially from the finished work. The tubular member 58 is made of a flexible, extensible material, preferably a substance which is resilient and elastic, such as rubber. It has been found that, after the central bar 26 has been slidably removed from the tube 58 when the masonry casting has been completed, the extensible, tubular member 58 may be readily removed by merely grasping the protruding end thereof and exerting an axial pull thereon. It 45 is thought that this novel and unobvious result

is due to the tendency of extensible materials to decrease in transverse dimension when they are stretched and, accordingly, for the tube to contract within the enclosing masonry and to pull away therefrom. This novel structure provides an improved and simplified screw clamp, all of the elements of which can be readily and completely removed from the finished masonry without the remotest possibility of damaging the work.

Attention is particularly directed to the fact that the screw clamp members shown in Figures 8 to 9 are employed to space the walls of the form, as well as to clamp them against interior expansive forces. To this end it will be noted that the whaler 60 is secured to the studding 38 by means of the sleeper blocks 62. The bar 26 is then laid on the top surface of the whaler and the staple 64 driven in place, as shown in Figure 10, so that it engages into the groove formed by the threads 66. Accordingly, the bar may be fixed with respect to the opposed, parallel whalers 60. In order that the clamping nuts 30 will exert a direct axial force upon the bar 26 a second whaler member or liner 68 is placed above the bar, as clearly shown in Figures 8 and 9, whereby the flat clamping face of the nut 30 engages the aligned edges of the members 66 and 68. According to the arrangement shown in Figure 8 the nails 18 securing the lower whaler in place are driven upwardly through the sleeper member 62 while, according to the alternative structure of Figure 9, they are shown as being driven downwardly. When proceeding in accordance with the aspect of the present invention, it is unnecessary to bore holes in the whalers or to provide spacing members of special dimension.

Figure 11 discloses the sectional appearance of the finished wall after the forms have been disassembled and the clamping screws removed therefrom with the resulting aperture sealed with mortar.

The bar 26, as shown in the enlarged view in Figure 10, is flattened on opposed sides 27 so that the threads thereof are interrupted on both sides. Rods of this kind can be readily made by flattening opposed sides of a round bar and then rolling threads thereon. It is preferred that the threads be extended completely from one end of the bar to the other so that the stock may be furnished in long pieces and then cut to the proper length in accordance with the demands of the particular work. The provision of the opposed, flattened sides 27 has numerous advantages. Among these is the fact that the bar can be readily gripped for twisting or removing from the work. This feature further renders the threads self-cleaning of rust and mortar by providing a free space into which the foreign materials are crowded by the threads on the nut.

The embodiment disclosed in Figure 12 is particularly useful in the fabrication of massive masonry structures which are poured or built up progressively in overlying sections. The upper portion of a hardened and set lower concrete section is indicated by the reference numeral 72. During the casting of this portion, bar members 74 having a hooked end 76 have been embedded in the masonry mass so that the threaded end 78 thereof projects from the finished vertical surface. At the same time a U-shaped anchor member 80 has been embedded in the upper surface of the mass at a point removed a substantial distance from the said vertical side. These two means serve to rigidly anchor and support

the side forms for pouring the next layer of masonry. The side forms comprise the form face or sheeting 82 stiffened by studding 38 joined by a plurality of liners or whalers 84, 86 and 88.

Attention is directed to the fact that the side forms are bored to receive the projecting threaded end 78 of the bar 74, the form being clamped in place by means of the nut 30. The form is further bored adjacent its upper end to receive the diagonally extending bar 90 having a hooked lower end 92 engaging in the U-shaped anchor 80 and threaded at its upper end as at 94 to receive the clamping nut 30. The form assembly is prevented from inclining inwardly by means of the brace bar 96 which engages in a block 98 fastened on the inner face of the form face 82. The brace bar 96 may, if desired, be removed from the position shown after the form has been partly filled with concrete. Attention is directed to the upper clamping bar 74 mounted in a suitable aperture in the form and positioned so that it will be surrounded by and embedded in the cast masonry. The dotted lines in the figure indicate the successive positioning of a further anchor member 80 for again supporting the forms during the casting of a subsequent superposed layer. After the masonry has hardened and set, the three nuts 30 are removed from the bars 74 and 90 whereupon the form can be readily removed from the work and again set up with respect to the upper anchor members 74 and 80 in the same manner, as has been hereinbefore described.

In use, the bar 90 need not be provided initially with the bent end 92. Preferably it may be furnished in a straight section and, after assembly with the form, it can be inserted under the anchor 80 and bent reversely, thus being readily adapted to connect with the anchor member regardless of its positioning.

Breakbacks 100 provided upon the bars 74 and 90 to facilitate readily snapping them off when their usefulness has ceased, comprise indentations clearly shown in Figure 14. Preferably these indentations are made by driving a sharp instrument into the bar, for example, as by cold forging, and it has been found that this structure renders it possible to break the bars with increased facility by twisting while at the same time the tensile strength of the bars is in no wise lessened.

Particular attention is directed to the fact that the breakbacks 100 are so positioned with respect to the structure that they reside slightly within the exterior surface of the finished masonry structure. Accordingly, the bars tend to twist or break off interiorly of the work, as shown in Figure 13, being thus protected from corrosion and capable of being readily sealed by pointing with a suitable mortar.

The present invention provides improved and highly simplified means for assembling forms for concrete work and the like and which completely eliminates the normal difficulties in assembling and disassembling the forms, as well as in removing the tying and spacing members from the cast masonry. When proceeding in accordance with the present invention it is unnecessary to apply inordinate pressures to accomplish disassembly such as would damage the finished work. The forms in all cases offer no difficulty in assembly and may be employed to space the various portions thereof, as well as tie them together against expansive forces.

It is thought that the invention and numerous

of its attendant advantages will be understood from the foregoing description and it is obvious that numerous changes may be made in the form, construction and arrangement of the several parts without departing from the spirit or scope of the invention, or sacrificing any of its attendant advantages, the form herein described being a preferred embodiment for the purpose of illustrating the invention.

The invention is hereby claimed as follows:

1. For use in combination with a form for molding concrete masonry or the like and having opposed, spaced wall sections providing a molding space therebetween, a clamp for joining the two sections comprising a longitudinally extending clamping member disposed between said sections, and an extensible, tubular member substantially enclosing the clamping member and being freely separable therefrom in a longitudinal direction, said tubular member having continuous, integral walls throughout its length, the clamping member comprising a bar having opposed, substantially flat, longitudinally extending faces, said bar having threads formed on the intermediate surfaces thereof with the said flat faces left plane, the threads extending continuously throughout the length of the bar.

2. In a form for casting and shaping masonry and the like, a pair of spaced walls providing a molding space therebetween, a clamping member extending between said walls and comprising a bar, and a sleeve axially slidably mounted on said bar, said sleeve being formed of a continuous, integral, resilient, rubber-like material and extending a substantial distance beyond the sides of the molding space sufficient to facilitate grasping thereof for free removal of the resilient tube from the final cast unit by a moderate axial pull.

3. For use in combination with a form for casting and shaping masonry and the like comprising a pair of spaced walls providing a molding space therebetween, a clamping member adapted to extend between the walls and beyond the said walls on the outer sides thereof and comprising a bar, said bar having a central section adapted to extend within said molding space and outer sections adapted to extend outwardly from said

walls, a sleeve axially slidably disposed on said bar, said sleeve being formed of resilient extensible rubber-like material and being disposed over said central section and a substantial portion of at least one of said outwardly extending sections of the bar to facilitate grasping thereof for free removal of the resilient tube from the final cast by a moderate axial pull.

4. For use in combination with a form for casting and shaping masonry and the like comprising a pair of spaced walls providing a molding space therebetween; a clamping member adapted to extend between the walls and beyond the said walls on the outer sides thereof and comprising a bar, said bar having a central section adapted to extend within said molding space and outer sections adapted to extend outwardly from said walls, a sleeve axially slidably disposed on said bar, said sleeve being formed of resilient extensible rubber-like material and being disposed over said central section and a substantial portion of said outer sections of the bar to facilitate grasping thereof for free removal of the resilient tube from the final cast by a moderate axial pull.

5. In a form for casting and shaping masonry and the like, a pair of spaced walls providing a molding space therebetween, a clamping member extending between said walls and comprising a bar, and a sleeve axially slidably mounted on said bar, said sleeve being formed of an extensible rubber-like material and extending a substantial distance beyond at least one side of the molding space sufficient to facilitate grasping thereof for free removal of the resilient tube from the final cast unit by a moderate axial pull.

6. A masonry structure comprising a unit having opposite spaced faces and a sleeve adapted to centrally receive a clamping bar and extending substantially between said opposed faces internally of said masonry unit, said sleeve being formed of extensible rubber-like material and having an extremity extending a substantial distance beyond one face of said masonry unit sufficient to facilitate grasping thereof for free removal of the resilient tube by a moderate axial pull.

GEORGE B. BOSCO.
